UNITED STATES PATENT OFFICE.

JOSEPH W. LUCIER, OF KANKAKEE, ILLINOIS, ASSIGNOR OF ONE-HALF TO HARRY L. TOPPING, OF KANKAKEE, ILLINOIS.

STOP MECHANISM.

1,389,367.

Specification of Letters Patent. Patented Aug. 30, 1921.

Application filed May 8, 1920. Serial No. 379,854.

To all whom it may concern:

Be it known that I, JOSEPH W. LUCIER, a citizen of the United States, residing at Kankakee, in the county of Kankakee and 5 State of Illinois, have invented certain new and useful Improvements in Stop Mechanism, of which the following is a specification, reference being had therein to the accompanying drawings.

10 This invention relates to improvements in sound reproducing machines, and has particular reference to stop mechanism for automatically arresting rotation of the turn-table and its superposed record, and at any predetermined point.

15 It is an object of this invention to provide a stop mechanism which can be operatively associated with various types of reproducing machines adapted to play different makes 20 of records.

Another object of the invention is the provision of a stop-mechanism which can readily be attached to existing types of machines.

A still further object within the contemplation of my invention is the provision of a stop-mechanism, certain in its operation and easily set by the operator, and adaptable to existing types of machines, whereby rotation of the turn-table is automatically controlled by movement of the tone-arm, the latter preferably carrying instrumentalities which co-act with instrumentalities carried by the turn-table actuating-mechanism, the controlling-mechanism being settable at the will of the operator, first, to arrest the turn-table and its superposed record at any predetermined point and, secondly, to govern the operation of the turn-table for various types of machines without requiring modification of the controlling-mechanism. In other words, the structure constituting the inventive concept in such that it is adaptable to various types of sound-reproducing machines without modifying the construction 40 in any regard, the structure including means for adjusting the parts to co-act according to the particular type of machine with which it is associated.

A still further object of the invention is 50 the provision of means whereby the structure, when once set to play a record, may operate again without requiring manual resetting of the parts.

With these and other more or less important objects in view, the invention resides in a structure which includes, preferably, a base

or support for trigger-mechanism that is adapted to be relatively stationary in respect to the normal movement of the tone-arm, the latter carrying means which, at a predetermined point in its travel over the record, becomes active in conjunction with the trigger-mechanism to arrest the turn-table and its superposed record; the instrumentalities carried by the tone-arm preferably including 60 a controlling device settable at the will of the operator to co-act with the trigger-mechanism according to the type of record which is being played on the machine.

In order that the invention may be clearly comprehended, the accompanying drawings are hereto appended; but these are, and are intended to be, merely illustrative of one embodiment of the invention, it being understood that the inventive concept is susceptible of considerable variation and modification without departing from its spirit or sacrificing any of its salient features or advantages.

In these drawings:

Figure 1 is a view in top plan of one embodiment of my invention;

Fig. 2 is a view in side elevation of the same;

Fig. 3 is a fragmentary view, partly in 85 vertical section, on the line 3—3, Fig. 4;

Fig. 4 is a view in front elevation, a portion of the mechanism being shown in dotted lines;

Fig. 5 is a detailed view, in bottom plan, 90 of a portion of the apparatus; and

Fig. 6 is a detailed view, in perspective, of certain coöperating parts.

Referring to these drawings, the numeral 1 designates the casing of a sound-reproducing machine, of any appropriate type and construction, which is provided with a turn-table 2 for supporting a phonograph record 3, having grooves 3^a, and a tone-arm 4 carrying a reproducer or sound-box 5.

100 Encircling the tone-arm 4 is a pointer supporting member or ring 5^a, formed with an upstanding portion or collar 6, threaded as at 6^a, and adapted to be rigidly secured to the tone-arm, as by screws 6^b. Carried by the member 5^a is a pointer-sustaining extension or arm 7.

110 In this instance, the tone arm is mounted in an annular bearing-member A which includes a base-portion A² securable to the casing 1 as by a series of screws A³, and also includes a vertical portion A⁴ adapted to en-

compass the tone-arm, as shown. Preferably and as shown, the bearing-member includes an internal cross-web A⁵. Upstanding from the cross-web is a pivot-post A⁶ which extends 5 through a cross-piece 4^a within the tone-arm, the post extending into a journal-boss 4^b in the tone-arm 4. The post A⁶ provides an additional means of maintaining the tone-arm for effective operation and against undesirable vibration as the tone-arm travels 10 over the record 3. It will be understood that the tone-arm is adapted to have free movement in the bearing-member A.

The bearing-member A constitutes a support for certain of the components, herein-after described, forming the stop-mechanism which characterizes my invention.

Preferably and as shown, the collar 6 of the ring 5^a has associated therewith a trip-carrying member or ring 8 provided with an outstanding plate or projection 9 on which is formed an ear 10. Pivotaly secured to the ear is one member 11^a of a toggle, the other member 11^b of which turns 25 on a pivot-washer 12 upstanding from the arm 7. Integral with or rigidly secured to the member 11^b of the toggle is a limit-setting member or pointer 13 which is settable by the operator at different positions on 30 the record to regulate the mechanism for stopping the turn-table 2 at any desired or required point.

Depending from the pointer 13 is a boss 14 forming a connection between the toggle-member 11^b and the pointer 13. The pointer and toggle-member 11^b pivot on a screw 16 threaded into the arm 7.

Depending from the plate 9, and near the inner portion thereof, is a bifurcated stud 40 17, in which is pivotally mounted a trip-sustaining member 18, movement of which is controlled by a spring 18^a. Upstanding from the member 18 is a trip 19, this extending through an aperture 9^a in the plate 45 9. Normally, the spring 18^a has a tendency to move the trip-sustaining member toward the underside of the plate 9, and means (presently to be described) are provided for varying the extent of movement of the member 18. It will be understood that the position 50 of the trip 19 is such as normally to be in the path of travel of the tone-arm as the same moves across the record and in order that it may engage the trip and operate the 55 parts, as will presently be described. The free end of the member 18 is provided with a catch 18^b, for a purpose now to be described.

Pivotaly mounted on the underside of the 60 plate 9 is a brake-member designated generally by the reference-character 20, and of hammer-like form. This brake-member is provided with a hammer 21 adapted, when the trip is actuated, to engage with and arrest 65 rotation of the turn-table. The hammer

is, preferably and as shown, provided with a facing of rubber, felt, or other resilient material 22, which aids in arresting rotation of the turn-table. Disposed at an angle to the hammer-member is an extension 23 provided with a beveled portion 23^a for the purpose of engaging the catch 18^b and holding it against movement until the tone-arm is brought into contact with the upstanding trip 19. A spring 24, secured (as by a screw 70 25) to the underside of plate 9, bears against the brake-member and is adapted when the trip 19 is engaged by the traveling tone-arm and rocks on its pivot so that the portion 20^a with its catch 18^b is pressed out of engagement with the beveled portion 23^a and permits the brake mechanism 20 to be forced by the spring 24, against the rotating turn-table and thereby stop the same.

Means are preferably provided for varying the extent of movement of the brake-member 20, and comprise a screw 26 threaded through the plate 9, adjacent the trip 19, and adapted to engage the brake. By raising or lowering this screw, the time of release of the hammer can be varied.

Preferably and as shown, means are provided for maintaining the movable ring 8 in proper operating position and comprise a ring-element 27 secured, as by screws 28^a 90 threaded therethrough and engaging the collar 6 of the supporting ring 5^a.

To maintain the trip-carrying ring 8 in spaced-apart relation to the base of the ring 5^a and to the holding ring 27, fiber washers 100 28 are inserted therebetween, as shown.

The structure, as above described, constitutes a trigger-mechanism which, by reason of being secured to the casing 1 of the machine is relatively stationary during the 105 traveling movement of the tone-arm. In order to operate this trigger-mechanism directly by the tone-arm, means are provided on the tone-arm that are engageable with the trigger-mechanism to operate the same 110 when the tone-arm has reached a predetermined position; and I shall herein refer to the components carried by the tone-arm as the trigger-actuating mechanism; it being understood that this mechanism travels with 115 the tone-arm in relation to the relatively stationary trigger-mechanism. This mechanism includes a settable disk-member 29 secured, as by a screw 30, to a portion of the tone-arm attached to a boss or stud 31 120 secured to the tone-arm. The disk carries two tripping pins 32 and 33, disposed at different distances from the axis of the disk and adapted to be disposed in the path of movement of the trip 19. These pins 32 125 and 33 are differently spaced from the axis of the disk 29, as shown, in order to adapt the structure for different types of records. As is well known, some types—such as the Pathe, for instance—are more difficult to 130

arrest in their movement; wherefore, in order to maintain the engagement of the trip 19 with one or another of these pins for a greater or lesser time, their arrangement 5 with respect to the axis of the disk has been developed as shown. When the pin 32, for instance, is positioned so as to be engaged by the trip 19, it—by reason of the fact that it is disposed nearer the disk's axis—will 10 vary the actuating movement of the trip 19 to such an extent that a greater amount of leverage will be provided and, thus, permit the hammer to impinge with greater force against the turn-table.

15 For the purpose of limiting the turning movement of the disk, pins 34 and 35 are mounted on the back thereof, which are adapted, when the disk 29 is turned, to engage a downwardly projecting finger 36, 20 mounted on the boss 31 and thus keep the disk 29 and the attached pins 32 and 33 in operating position.

As above pointed out, it has been found in practice that certain makes of records, 25 such as the Pathe (which are played with so-called "sapphire" points or balls) require a stronger braking action to insure successful operation of the stop than do records employing steel needles or "diamond" points 30 as the reproducing medium. Consequently, when playing records with "sapphire" points, the disk 29 is revolved so that it will bring pin 32 into register with the trip 19 so that greater leverage will be provided 35 and, consequently, the hammer will be forced against the turn-table with more force and thus insure positive stopping of the turn-table, as above pointed out.

Operation: After the record has been 40 placed on the turn-table, the pointer is brought to the position on the record where it is desired to trip the brake. By moving the pointer in this manner, it will be observed that, through the connected lever arrangement 11, the plate 9, with the up-standing-pin 19, will be moved to the left. If the record is being played with a "sapphire" ball, the disk 29 on the tone-arm is 45 revolved to bring pin 33—which is placed nearer the outer edge of the disk 29 than pin 32 and is so limited in its movement by pin 34 on the reverse side of a disk 29 contacting therewith—into such a position that it will be engaged by the trip 19 sooner 50 than when pin 32 is turned for engagement with the trip and, thus, advance the instant of engagement of the brake-member with the turn-table to effect its earlier operation which, in practice, has been found 55 desirable when playing records with hill-and-dale grooves. When the tone-arm, with its disk 29, has reached that point in its travel where the predetermined pin 32 or 60 33 contacts with the upstanding portion 19, 65 the pressure of the pin against said up-

standing portion will force the same to rock or yield sufficiently to release the catch 20, permitting the hammer 21 to be forced, by means of the spring 24, against the turn-table and, thus, bring the turn-table and its 70 superposed record to a complete stop.

If it is desired to place a new record on the machine, the pointer 11 must be turned so that it will permit withdrawal of the record then on the turn-table. In so moving the pointer, the projection 9 is, through the toggle-lever arrangement, carried to the right, forcing the hammer 21 against the turn-table and, thus, causing it to automatically re-lock itself by pressing the extension 75 23 on the hammer and causing the beveled portion 23^a to ride over the catch 18^b. Thus it will be seen that the stop is automatically re-set. After the new record has been placed on the turn-table, the pointer is again 80 brought to the proper position on the record. By moving the pointer to the right and over to about the center of the record, it will carry the plate 9, with its attached 85 brake 20, out of engagement with the turn-table and permit further rotation.

From the foregoing description, it will be observed that I have devised an exceedingly simple arrangement whereby positive stopping of a phonograph record is assured, and 90 whereby records requiring a stronger braking action to insure positive stopping thereof will also be attained.

While I have shown my invention in the embodiment illustrated, it is to be understood that many changes may be made in the same without departing from the spirit thereof or its scope, as set forth in the 100 claims.

What I claim is:

1. Stop mechanism for sound-reproducing machines having a turn-table, a tone-arm and a support therefor which is relatively stationary in respect to the tone-arm, the stop-mechanism including co-acting means carried by the support and the tone-arm and operable when the tone-arm reaches a predetermined position in its travel over the 105 turn-table.

2. Stop mechanism for sound-reproducing machines having a turn-table, a tone-arm movable over the turn-table, and a bearing-structure associated with the tone-arm and relatively stationary in respect thereto; the stop mechanism including trigger-mechanism carried by the bearing structure, and a trip-device carried by the tone-arm and engageable with the trigger-mechanism when the tone-arm reaches a predetermined position in its travel over the turn-table.

3. Stop mechanism for sound-reproducing machines having a turn-table, a tone-arm movable over the turn-table and a bearing-structure in which the tone-arm is mounted and which is relatively stationary in respect 130

to the tone-arm; the stop mechanism including a trigger-device carried by and relatively stationary with the bearing-structure, and a trip-device carried by and movable 5 with the tone-arm and movable thereby into engagement with the trigger-mechanism for actuating the same.

4. Stop mechanism for reproducing devices which include a turn-table, a tone-arm 10 and a bearing-structure for the tone-arm, the stop-mechanism including a trigger-mechanism associated with the bearing-structure and relatively stationary thereon with respect to movement of the tone-arm over the 15 turn-table, and a trip-device carried by the tone-arm and settable at the will of the operator to provide a variable engagement between it and the trigger-mechanism for actuating the latter.

20 5. Stop mechanism for reproducing devices which include a turn-table, a tone-arm and a bearing-structure for a tone-arm, the stop-mechanism including a trigger-mechanism associated with the bearing-structure 25 and relatively stationary thereon with respect to movement of the tone-arm over the turn-table, a trip-device carried by the tone-arm and settable at the will of the operator to provide a variable engagement between it 30 and the trigger-mechanism for actuating the latter, and brake-mechanism associated with the trigger-mechanism and operable upon the turn-table when the trigger-mechanism is rendered active by the trip-device.

35 6. Stop mechanism for sound-reproducing devices which include a turn-table, a tone-arm movable over the same and a bearing-structure associated with the tone-arm and relatively stationary in respect thereto; 40 the stop-mechanism including a trigger-mechanism, a brake-device associated with the trigger-mechanism and rendered active thereby to engage the turn-table, and a trip-device associated with and positionable by 45 the tone-arm into engagement with the trigger-mechanism to operate the same and thereby set the brake-device into motion for engagement with the turn-table.

7. Stop mechanism for sound-reproducing 50 devices which include a turn-table, a tone-arm movable over the same and a bearing-structure associated with the tone-arm and relatively stationary in respect thereto; the stop-mechanism including a trigger-mechanism, a brake-device associated with the 55 trigger-mechanism and rendered active thereby to engage the turn-table, and a trip-device associated with and positionable by the tone-arm into engagement with the trigger-mechanism to operate the same and thereby set the brake-device into motion for 60 engagement with the turn-table, the trip-device including a settable disk, and stops thereon spaced-apart different distances 65 from the axis of the disk to provide a plu-

rality of points of engagement between the disk and the trigger-mechanism.

8. Stop mechanism for sound-reproducing devices having a turn-table and tone-arm, said mechanism comprising an actuating 70 member associated with the tone-arm, a support also associated with the tone-arm, brake mechanism associated with the turn-table and movably mounted on the support, a limit-setting member disposed on the support, a connection between the limit-setting member and the brake mechanism whereby movement of the limit-setting member positions the brake mechanism, and a trip member associated with the brake mechanism 80 and positioned in the path of the actuating member.

9. Stop mechanism for sound-reproducing devices having a turn-table and tone-arm, said mechanism comprising a plurality of 85 components, one component including an actuating member associated with the tone-arm, another component including a support also associated with the tone-arm, brake mechanism associated with the turn-table 90 and movably mounted on the support, a limit-setting member disposed on the support, a connection between the limit-setting member and the brake mechanism whereby movement of the limit-setting member positions the brake mechanism, and a trip member associated with the brake mechanism and positioned in the path of the actuating member.

10. Stop mechanism for sound-reproducing 100 devices having a turn-table and tone-arm, said mechanism comprising a plurality of components, one component including an actuating member associated with the tone-arm, another component including a support 105 also associated with the tone-arm, locking means associated with the support, brake-mechanism associated with the turn-table and movably mounted on the support, a limit-setting member disposed on the support, a connection between the limit-setting member and the brake mechanism whereby movement of the limit-setting member positions the brake mechanism, and a trip member associated with the brake mechanism 110 and positioned in the path of the actuating member.

11. Stop mechanism for sound-reproducing 115 devices having a turn-table and tone-arm, said mechanism comprising an actuating member associated with the tone-arm and provided with a plurality of pins, a support also associated with the tone-arm, brake mechanism associated with the turn-table and movably mounted on the support, a limit-setting member disposed on the support, a connection between the limit-setting member and the brake mechanism whereby movement of the limit-setting member positions the brake mechanism, and a trip member 125 associated with the brake mechanism and positioned in the path of the actuating member.

120

ber associated with the brake-mechanism and positioned in the path of the actuating member.

12. Stop mechanism for sound-reproducing devices having a turn-table and tone-arm, said mechanism comprising an actuating member rotatably mounted on the tone-arm, a support also associated with the tone-arm, brake mechanism associated with the

- 10 turn-table and movably mounted on the support, a limit-setting member disposed on the support, a connection between the limit-setting member and the brake-mechanism whereby movement of the limit-setting member 70 positions the brake mechanism, and a trip member associated with the brake mechanism and positioned in the path of the actuating member.
- 15 13. Stop mechanism for sound-reproducing devices having a turn-table and tone-arm, said mechanism comprising an actuating member rotatably mounted on the tone-arm and provided with a plurality of tripping pins, a support also associated with the 75 tone-arm, brake-mechanism associated with the turn-table and movably mounted on the support, a limit-setting member disposed on the support, a connection between the limit-setting member and the brake mechanism whereby movement of the limit-setting member 80 positions the brake mechanism, and a trip member associated with the brake mechanism and positioned in the path of the actuating member.

- 20 14. Stop mechanism for sound-reproducing devices having a turn-table and tone-arm, said mechanism comprising an actuating member associated with the tone-arm and provided with a plurality of pins, a 85 support also associated with the tone-arm, brake mechanism associated with the turn-table and movably mounted on the support, a limit-setting member disposed on the support, a connection between the limit-setting member and the brake mechanism whereby movement of the limit-setting member 90 positions the brake mechanism, and a trip member associated with the brake mechanism and positioned in the path of the actuating member.
- 25 15. Stop mechanism for sound-reproducing devices having a turn-table and tone-arm, said mechanism comprising an actuating member associated with the tone-arm and provided with a plurality of pins, a support also associated with the tone-arm, 95 brake mechanism associated with the turn-table and movably mounted on the support, a limit-setting member disposed on the support, a connection between the limit-setting member and the brake mechanism whereby movement of the limit-setting member 100 positions the brake mechanism, and a trip member associated with the brake mechanism and positioned in the path of the actuating member.

- 30 16. Stop mechanism for sound-reproducing devices having a turn-table and tone-arm, said mechanism comprising an actuating member associated with the tone-arm and provided with a plurality of pins, a support also associated with the tone-arm, 105 brake mechanism associated with the turn-table and movably mounted on the support, a limit-setting member disposed on the support, a connection between the limit-setting member and the brake mechanism whereby movement of the limit-setting member 110 positions the brake mechanism, and a trip member associated with the brake mechanism and positioned in the path of the actuating member; said actuating member adapted to be rotated to bring one of the pins in the path of movement of the trip-member.
- 35 17. Stop mechanism for sound-reproducing devices having a turn-table and tone-arm, said mechanism comprising an actuating member associated with the tone-arm and provided with an upstanding portion, a support also associated with the tone-arm, 115 brake mechanism associated with the turn-table and movably mounted on the support, a limit-setting member disposed on the support, a connection between the limit-setting member and the brake mechanism whereby movement of the limit-setting member 120 positions the brake mechanism, and a trip member associated with the brake mechanism and positioned in the path of movement of the trip-member.

- 40 18. Stop mechanism for sound-reproducing devices having a turn-table and tone-arm, said mechanism comprising an actuating member associated with the tone-arm, a support also associated with the tone-arm and provided with an upstanding portion, a 125 support also associated with the tone-arm, 130 brake mechanism associated with the turn-table and movably mounted on the support, a limit-setting member disposed on the support, a connection between the limit-setting member and the brake mechanism whereby movement of the limit-setting member positions the brake mechanism, and a trip

member associated with the brake mechanism and positioned in the path of the actuating member.

19. Stop mechanism for sound-reproducing devices having a turn-table and tone-arm, said mechanism comprising an actuating member associated with the tone arm, a support also associated with the tone-arm and provided with an upstanding threaded portion, brake mechanism associated with the turn-table and movably mounted on the support, a limit-setting member disposed on the support, a connection between the limit-setting member and the brake mechanism whereby movement of the limit-setting member 75 positions the brake mechanism, and a trip member associated with the brake mechanism and positioned in the path of the actuating member.

20 21. Stop mechanism for sound-reproducing devices including a bearing-structure comprising a pointer-supporting ring-member, a pointer pivotally sustained by the ring-member, a toggle-device connected to the pointer, a movable ring-member to 90 which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip, a series of stops disposed thereon, and means for limiting the rotative movement of the disk for positioning the stops thereon in relation to the path of movement of the trip.

25 22. Stop mechanism for sound-reproducing devices including a bearing-structure 105 comprising a pointer-supporting ring-member formed with an extension, a pointer pivotally sustained by the ring-member, a toggle-device connected to the pointer, a movable ring-member to which the toggle-device 110 is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip, a series of stops disposed thereon, and means for limiting the rotative movement 115 of the disk for positioning the stops thereon in relation to the path of movement of the trip.

30 23. Stop mechanism for sound-reproducing devices including a bearing-structure 120 comprising a pointer-supporting ring-member, a pointer pivotally sustained by the ring-member, a toggle-device connected to the pointer, a movable ring-member encompassing the pointer-sustaining ring-member 125

130

and to which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip, a series of stops disposed thereon, and means for limiting the rotative movement of the disk for positioning the stops thereon in relation to the path of movement of the trip.

20. Stop mechanism for sound-reproducing devices including a bearing-structure comprising a pointer-supporting ring-member, a pointer pivotally sustained by the ring-member, a toggle-device connected to the pointer, a movable ring-member to which the toggle-device is connected, a brake-supporting plate carried by the movable ring-member, a spring-pressed brake-member on the plate, a trip-sustaining member pivoted to the plate, a trip upstanding from the trip-sustaining member and projecting through the plate, a catch on the trip-sustaining member engageable with the brake-member, a trip-device operatively associated with the trip, a series of stops disposed thereon, and means for limiting the rotative movement of the disk for positioning the stops thereon in relation to the path of movement of the trip.

21. Stop mechanism for sound-reproducing devices including a bearing-structure comprising a pointer-supporting ring-member, a pointer pivotally sustained by the ring-member, a toggle-device connected to the pointer, a movable ring-member to which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip and movable in relation thereto, a series of stops disposed thereon, and means for limiting the rotative movement of the disk for positioning the stops thereon in relation to the path of movement of the trip.

22. Stop mechanism for sound-reproducing devices including a bearing-structure comprising a pointer-supporting ring-member, a pointer pivotally sustained by the ring-member, a toggle-device connected to the pointer, a movable ring-member to which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining

on the trip-sustaining member engageable with the brake-member, a trip-device operatively associated with the trip and including a rotatable disk, a series of stops disposed thereon, and means for limiting the rotative movement of the disk for positioning the stops thereon in relation to the path of movement of the trip.

23. Stop mechanism for sound-reproducing devices including a bearing-structure comprising a pointer-supporting ring-member, a pointer pivotally sustained by the ring-member, a toggle-device connected to the pointer, a movable ring-member to which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip, a series of stops disposed thereon at different distances from its axis, and means for limiting the rotative movement of the disk for positioning the stops thereon in relation to the path of movement of the trip.

24. Stop mechanism for sound-reproducing devices including a bearing-structure comprising a pointer-supporting ring-member, a pointer pivotally sustained by the ring-member, a toggle-device connected to the pointer, a movable ring-member to which the toggle-device is connected, a brake-supporting plate carried by the movable ring-member, a spring-pressed brake-member on the plate, a trip-sustaining member pivoted to the plate, a trip upstanding from the trip-sustaining member, a catch on the trip-sustaining member engageable with the brake-member, a trip-device operatively associated with the trip, a series of stops disposed thereon, and means for predeterminedly limiting the rotative movement of the disk for positioning the stops thereon in relation to the path of movement of the trip.

25. Stop mechanism for sound-reproducing devices including a bearing-structure comprising a pointer-supporting ring-member formed with an extension, a pointer pivotally sustained by the ring-member, a toggle-device connected to the pointer, a movable ring-member encompassing the pointer-sustaining ring-member and to which the toggle-device is connected, a brake-supporting plate carried by the movable ring-member, a spring-pressed brake-member on the plate, a trip-sustaining member pivoted to the plate, a trip upstanding from the trip-sustaining member and projecting through the plate, a catch on the trip-sustaining member engageable with the brake-member, a trip-device operatively associated with the trip.

trip and movable in relation thereto and including a rotatable disk, a series of stops disposed thereon at different distances from its axis, and means for predeterminately 5 limiting the rotative movement of the disk for positioning the stops thereon in relation to the path of movement of the trip.

In testimony whereof I affix my signature in presence of two witnesses.

JOSEPH W. LUCIER.

Witnesses:

W. A. SCHNEIDER,
VELERIE GODE.
